METHOD OF GROUNDING SHIELDING TAPE
AT TERMINAL OF INSULATED CONDUCTORS

Bjorn Jore, Hastings upon Hudson, N. Y., assignor to Anaconda Wire & Cable Company, New York, N. Y., a corporation of Delaware

Application December 26, 1934, Serial No. 759,145

7 Claims. (Cl. 173—324)

My invention relates to terminals for insulated electric cables or conductors that are shielded with a metallic envelop which in turn is protected from the air and the elements, and it relates more particularly to means and methods for grounding such metallic shields.

Heretofore shields of the above type have been grounded by removing the protective covering about the shield at a distance from its connection to a terminal connector and then clamping onto the metallic surface of the shield thus exposed a clamp which is in turn connected to ground. The removal of the protective covering, usually an impregnated braided material, exposed the metallic sheath to the atmosphere and permitted moisture to enter beneath the outer protective covering and penetrate between the insulation and the shielding tape. This exposed the insulation to deterioration and sometimes to ultimate dielectric breakdown.

In my present invention these defects are obviated and a grounding means and method are provided in which the metallic shield and the insulation between the shield and the conductor are covered and protected against the entrance of moisture or air or other disintegrating or destructive agents.

The various features of my invention are illustrated in the accompanying drawing in which Fig. 1 shows a conductor and shield terminal embodying a preferred form of the invention; Figs. 2 and 3 are views showing the shield in successive stages of construction; and Fig. 4 is a longitudinal section, on a larger scale, of the cable and grounding shield and connections.

In the accompanying drawing the invention is illustrated as applied to a cable having a central core 10 and an enclosing sheath 11 of rubber or other suitable insulating composition. The end 40 of the conductor 10 is received in and secured to a terminal lug 12. The insulation 11 is continued to approximately the lug 12, a wrapping 13 of tape being provided between the lug 12 and the insulation 11. It will be understood that this cable construction is shown merely for purposes of illustration and that other arrangements of conductor and insulation may be used.

The cable also has a metallic sheath 14 wrapped or laid or braided about the insulation 11. The shield 14 is in turn covered by a layer 15 of protective material to prevent injury to the shield insulation and to prevent the access to the latter of moisture or corrosive agents. In forming a grounding terminal for the shield 14 the latter is cut back to a sufficient distance from the lug 12

and terminates as indicated at 16 in Fig. 4. The protective covering 15 is cut back somewhat further so as to expose the shield for a short distance, as for example one-half inch. A wrapping 17 of insulating tape is then formed on the insulating jacket 11 beginning at the point 16 and continuing for a short distance on the insulation. This wrapping 17 gradually increases in diameter from the point 16 where its diameter approaches that of the jacket 11 to a maximum and then decreases. The shield 14 is then provided with an extension of gradually increasing diameter by wrapping the exposed end of the sheath between the point 16 and the end of the covering 15 with a suitable metallic element, as for example a metal braid or mesh 18. This may be done by wrapping one end of the braid 18 about the exposed surface of the shield and then in helical fashion onto the expanding surface of the tape winding 17. It will be apparent that with this construction the metallic enclosing sheath element is expanded so that its edge has a diameter considerably greater than that of a shield 14 and is separated from the conductor 10 by an added quantity of insulation thereby preventing a concentration of stress on the insulation 11 at the termination of the extended shield 18.

A band or braid 19 of conducting metal, such as copper, is then laid longitudinally along the conical structure 18 overlapping the surface of the shield 14 and is secured to the conical mesh structure 18 and to the exposed end of the shield thus forming a unitary structure and a good electrical connection between the three elements. This may be accomplished by soldering.

Several layers of rubber tape are then wrapped over the cone and ground lead from the end of the protective coating 15 to approximately the termination of the metal cone. The band or braid 19 is then bent back over the rubber tape and for a short distance onto the covering 15 and is then secured to a terminal connector 20. The braid 19 is then filled and saturated with a rubber cementing compound so that the interstices are completely filled and the surface completely coated. Several layers 21 of rubber tape are then applied by wrapping them around the structure so as to cover the braided lead or band 19 throughout its entire exposed length from the clamp 20. A seal against the entrance of moisture is formed between the braided copper lead 19, the rubber tape and the structure 18. Layers 22 of friction tape are then wrapped over the rubber tape and the entire structure is painted with a water-proof paint to make a double seal against the entrance

of moisture or destructive reagents. Through the above construction, therefore, the part of the shield and terminal parts of the insulating material at which the connection is made to a ground 5 clamp are thoroughly covered and sealed against the entrance of moisture or destructive agents while at the same time a very effective electrical connection is made from the shield to ground.

What I claim is:

10 1. A cable terminal comprising a conductor, insulation enclosing said conductor, a metallic shield encircling said insulation and terminating short of the end of said insulation, a protective covering of insulating material for said shield terminating short of the end of said shield and a flaring metallic extension on said shield beyond the end of said protective covering, a lead wire extending from said flaring extension to a ground 15 clamp and a protective covering of water resistant material enclosing said lead and said flaring extension and sealing the latter from the entrance of moisture.

20 2. A cable terminal comprising a conductor, an insulation for said conductor, a metallic shield enclosing said insulation and terminating short of the end thereof, a protective covering of insulating material for said shield, said insulation being increased in diameter for a short 25 distance beyond the end of said shield, a metallic 30 wrapping extending from the end of said shield onto said enlarged insulation, a protective covering of water resistant insulating material for said wrapping and a lead extending through said covering, and means for sealing said lead to prevent 35 entrance of moisture to said metallic wrappings.

30 3. A cable terminal comprising a conductor, an insulation for said conductor, a protective metallic shield about said insulation and terminating short of the end of said conductor, a protective 40 covering of water resistant insulating material for said shield, said insulation being increased in diameter beyond the end of said metallic shield and a metallic extension from said shield onto the enlarged insulation, a protective covering of water 45 resistant insulating material for said extension, a braided wire lead from said extension through said protective covering of said exten-

sion, said lead being impregnated and filled with moisture-proofing material to seal said extension from moisture.

4. A cable terminal comprising a conductor, an insulation for said conductor, a protective metallic shield about said insulation and terminating short of the end of said conductor, a water resistant insulating protective covering for said shield, said insulation being increased in diameter beyond the end of said metallic shield and a metallic extension from said shield onto the enlarged insulation, a water resistant insulating protective covering for said extension, a braided wire lead from said extension through said protective covering, said lead being impregnated and filled with moisture-proofing material to seal said extension from moisture, said lead and extension and shield being secured together by solder.

5. The construction of claim 3 in which said lead extends backwardly over said protective covering and a clamp secured to said lead and secured on said cable.

6. The construction of claim 3 in which said lead extends backwardly over said protective covering and a clamp secured to said lead and secured on said cable, said returning lead being embedded in protective material to prevent entrance of moisture.

7. A cable terminal construction which comprises a conductor, a securing terminal for said conductor, insulation enclosing said conductor and the joining end of said terminal, a metallic protective sheath on said insulation terminating at a distance from said securing terminal, a water resistant insulating covering to protect said metallic shield from the atmosphere, said insulation flaring outwardly to an increased diameter beyond the end of said protective sheath, a metallic extension from said sheath onto said flaring insulation, a clamp on said cable short of the end of said metallic sheath and a connection from said shield extension to said clamp and a water resistant insulating protective material enclosing said extension and said connection and sealing said extension from moisture.
